UNITED STATES PATENT OFFICE.

MICHAEL F. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

Original application filed November 4, 1920, Serial No. 421,750. Divided and this application filed October 18, 1923. Serial No. 669,427.

This invention relates to improvements in turn shoe making and more particularly to a novel method of preparing turn soles for lasting which adds quality to the finished 5 shoe and perfects the shoe making process.

Heretofore, in order to secure proper operative relation between the needle and the work during the sole-sewing operation, it has been the practice to mould or break 10 down the margins of turn soles before the soles have been secured to the last, by means of a machine which feeds the margin of the sole progressively past the moulding tools such, for example, as the moulding machine 15 disclosed in Letters Patent of the United States, No. 1,110,637, granted September 15, 1914, on the application of William C. Meyer. After being moulded the soles are usually stacked one on top of another and it 20 has been found that owing to the necessary delay before the assembling operation is performed the moulded margins of the soles have a tendency to return to their normal flat condition. Should this flattening of the 25 margin occur there is interference with the action of the needle during the upper sewing operation resulting in a displaced seam and a crippled shoe.

In view of the foregoing, an object of the 30 present invention is to improve the method of making turn shoes in a manner that will insure a location of the seam, which secures the upper to the sole, at the base of the marginal sewing-rib or shoulder, or in such 35 marginal location on unribbed turn soles as will preserve the proper outline and desired appearance of the shoe.

By the present method it is proposed to 40 assemble the turn sole blank with the last, then mould, or break down, the margin of the sole to prepare it for the upper sewing operation and, without removing the sole, to assemble and last the upper in position over the broken down margin. Those skilled in 45 the art are aware that in making turn shoes two lasts are used, the first last having a bottom of less area than the area of the turn sole. After assembly with such a last the margin of the sole projects beyond the edge 50 of the last and the relative proportions of the last and sole are such that the edge of the last lies along the margin of the sole at the line where the angular moulding break should properly be made. The edge of the

last may, therefore, conveniently be used as 55 an anvil over which the margin of the sole may correctly be moulded. With the sole thus moulded, and before an opportunity is given for a return of the moulded margin to its original condition, the remainder of the 60 shoe is assembled on the last, the upper lasted in place, and the shoe sewed. In completing the turn shoe, the usual method is followed.

The method may be practised in making 65 turn shoes in which either channelled or unchannelled soles are embodied; and it has been found advantageous to perform the margin moulding operation in two stages, i. e. a side moulding operation and a toe 70 moulding operation. The sole margins at 75 the sides of the sole, having slight curves, can be broken down with greater facility and accuracy by pressure applied progressively to small portions of the area to be moulded, while the more sharply curved toe portion of the sole, especially where the sole is of the peaked toe type, can be broken down with greater facility and accuracy by pressure applied simultaneously over the whole 80 area about the toe, thus avoiding any dragging effect of a progressively moving tool which the sharp curvature of the sole at this point might inadequately enable it to support.

A machine for effectively moulding the 85 margins of turn soles, after assembly on the last, is disclosed in my co-pending application, Serial No. 421,750, filed November 4, 1920, of which this application is a division. It is preferred to use a machine of the type 90 disclosed in said parent application to perform the step of breaking down the margin of the sole while on the last, and a description of that machine will assist in understanding the present method. The machine 95 shown is a nurling machine of the general type disclosed in Letters Patent of the United States, No. 768,560, granted August 23, 1904, to Louis A. Casgrain, properly modified to suit the requirements of the 100 present invention.

In the drawings, Figure 1 is a view partially in side elevation and partially in section, of the upper portion of a machine of the type above specified; Fig. 2 is a view, in 105 front elevation and on an enlarged scale, of the operating instrumentalities of the machine, showing a last having a turn sole se-

cured thereto in position to be operated upon; Fig. 3 is an inverted plan view of the moulding tool for operating upon the toe of the sole; and Fig. 4 is a detail plan view 5 of the work support or guide.

The frame 10 of the machine, the face plate 12, the tool-carrier 14, and the rotary hammer 16, mounted on the driving shaft 18 for imparting a rapid succession of percussive blows to the tool-carrier, all may be, and preferably are, of the same design as like parts in the patent to Casgrain, hereinbefore referred to. The driving shaft 18 is provided with the usual fast and loose 15 pulleys, (not shown) for controlling its rotation. In accordance with the present method, the work is to be manually supported and fed as it is presented to the operating instrumentalities of the machine, 20 and consequently the present machine is not provided with a work-table or with a work-feeding device as in the machine of said patent to Casgrain.

The moulding tool which operates upon 25 the opposite lateral edge portions of the sole is indicated at 24, in Figs. 1 and 2. The moulding tool 24 comprises a rectangular block which is rigidly secured to the tool carrier 14 to vibrate rapidly therewith as 30 the latter is acted upon by the rotary hammer 16. To this end a hole 26 (Fig. 1) is bored transversely through the moulding tool 24 to receive a cylindrical stud 28, conveniently formed by machining a tool-sus- 35 taining projection with which the tool-carrier 14 of said nurling machine is provided. The tool 24 is located, with its length vertically disposed, by means of a shoulder 30 (Fig. 1) which is formed on the tool-carrier 10 to engage the upper end of the tool. The tool 24 is rigidly secured to the tool-carrier by means of a binding screw 32 that is threaded into an axial recess in the stud 28, the head of the screw 32 bearing against 45 a washer 34 which, in turn, bears against the front face of the tool. The moulding of the lateral margins of the sole is performed by one or more moulding faces at the lower end of the moulding tool 24, such 50 as are indicated at 38 and 40 in Fig. 2. These moulding faces are so proportioned as to engage the margin of the sole throughout only a comparatively small portion of its length at one time and are shaped to 55 impart the desired amount of transverse curvature thereto. In operation the sole is slowly drawn across the moulding face of the rapidly vibrating moulding tool 24, the operator preferably first presenting to said 60 face the rearmost point in that portion of the lateral margin which is to be moulded and then slowly drawing the last forwardly to progressively mould the sole margin until the tool reaches a point near the toe of the 65 sole. The breaking down may be aided by

rubbing the sole back and forth under the tool.

To avoid the necessity of turning the last end for end, after one lateral edge of the sole has been moulded, in order to bring 70 the opposite lateral edge thereof into the field of operation of the moulding tool, it is preferred to provide a pair of oppositely disposed moulding faces upon the tool 24. To this end the moulding face 38 is formed 75 at the left side of the moulding tool and arranged to operate upon the margin of the sole at one side and a similar moulding face 40 is formed at the right side of the moulding tool and arranged to operate upon the 80 margin of the sole at the other side. With this construction after one lateral edge of the sole has been operated upon by one of the moulding faces, the operator may readily present the opposite lateral edge 85 of the sole to the other moulding face by merely shifting the sole laterally beneath the tool. Thus the operator is relieved of the extra labor involved in the turning of the last, and considerable time is saved at 90 each sole moulding operation.

To assist in locating the sole relatively to the moulding tool 24, and to maintain the sole in position to receive the blows delivered by the moulding tool and at the proper transverse angle for the most advantageous operation thereof, an abutment is provided against which the upper or exposed face of the sole may be pressed. The abutment, or sole support, is carried at the 95 lower end of a vertical post 44 which is received in a socket formed in a block 46, the latter corresponding to a similar block in the machine of the patent to Casgrain, hereinbefore referred to. The post 44 is rigidly 100 but adjustably secured in the socket of the block 46 by means of a suitable clamping screw 47, this construction permitting such vertical adjustment of the support relatively to the moulding tool 24 as may be required in order to secure the best results from the action of said tool. As best shown in Fig. 4, the sole support comprises a yoke-shaped member having parallel work-engaging arms 42 which project horizontally on opposite sides of the moulding tool 24. The arms 42 are adapted, by engagement with the upper face of the sole as the latter is pressed upwardly against said arms by the operative during the moulding operation, to locate the sole vertically and position it at the proper transverse angle for the moulding operation. The arms 42 are curved longitudinally, as shown in Fig. 1, to permit them to engage the face of the sole margin at the shank of a sole, if it is desired to mould said portion of the margin. The lower face of each arm 42 is disposed transversely at a slight angle to the horizontal 110 to position the sole transversely at the angle 115 120 125 130

illustrated in Fig. 2, since it has been found that the margin may be more readily moulded into the required transverse curvature when the sole is thus supported. The 5 width of each arm 42 is such as to provide a firm support for enabling the operative to hold the sole at the proper height and angle to receive the blows delivered by the tool. To reduce friction between the arms 10 42 and the sole as the latter is drawn across said arms, and also to avoid the closing of the channel in the sole by the arms, the lower face of each arm is cut away, as indicated at 48 in Fig. 2, so that it will engage 15 the sole upon opposite sides of the channel but will not rub against the channel flap.

It is difficult, especially when operating upon soles having pointed toes, for the operative to swing the last to effect the 20 moulding of the margin at the tip of the toe without injuring the sole. In accordance with this invention, conveniently before or after the opposite marginal portions of the sole have been moulded by drawing said 25 portions successively across the moulding faces on the tool 24, the marginal portion about the tip of the toe is presented to a second moulding tool 50 which is secured to the upper portion of the moulding tool 30 24 and vibrates with the latter. The tool 50 is of substantial V-shape as shown in Fig. 3, to conform to the shape of the toe, and is provided with a cylindrical projection 52 which is received in a hole bored 35 35 transversely through the upper portion of the tool 24, and securely fastened therein by means of a suitable binding stud 54 (Figs. 1 and 2). The forks forming the 40 sides of the tool 50 project forwardly from the tool 24 in a substantially horizontal plane, and the lower or acting side is curved transversely to form a continuous concave 45 moulding face similar to the faces 38 and 40 of the tool 24. The particular cross-sections of the lower or acting faces of both of the moulding tools will vary since the tools are shaped to conform to the requirements of the manufacturer.

Before or after both lateral edges of the 50 sole have been operated upon by the moulding tool 24, the toe of the sole is presented to the rapidly vibrating toe moulding tool 50, the operator pressing upwardly on the last to hold the sole against the under 55 moulding face of the tool, and is held in contact therewith until the projecting margin about the tip of the toe is moulded or broken down over the edge of the last to the required extent. It will be observed 60 that the moulding tool 50 is located in front of and above the plane of the abutment 42 to avoid possibility of interference by the latter with the moulding operation at the toe.

When, in accordance with the usual custom, the margin of a turn sole is moulded

before the sole is secured to the last, there is necessarily considerable delay and additional handling of the sole before the upper sewing operation. Largely on account of this delay and partly on account of the way 70 in which the soles are handled after being moulded and before being secured to the last in the assembling operation, there is a marked tendency for the moulded margin to return to its normal flat condition, as 75 hereinbefore set forth. If, however, the sole is secured to the last before its margin is moulded, no such tendency is present since the upper may be immediately assembled on the last with the sole and lasted, making 80 the shoe at once ready for the performance of the upper sewing operation.

It will be recognized by those skilled in the art that the moulding of the margin of a turn sole after the sole has been secured to 85 the last is accomplished rapidly and effectively by practising the above described method, and that either the lateral portion of the margin or the toe may be moulded first, as the operator may elect, without 90 detracting from the final result.

In turn shoemaking the first last is reduced in size so that its bottom edge is opposite the shoulder on the flesh side of the sole which forms the striking shoulder for 95 the needle. Thus the last edge is properly located to act as the anvil about which the angle of the break should be made in the margin moulding operation. As a result, the moulded margin always is correctly located or, vice versa, the last always is correctly positioned relatively to the sole. The immediate lasting of the upper preserves the mould in the margin which is made by the machine, thereby insuring a properly 100 shaped shoe and a well formed seam.

Having thus described the novel method, through which former methods are perfected and superior shoemaking is attained, and the preferred manner of practising it, 110 what is claimed as new, is:—

1. The method of preparing turn soles for lasting which comprises assembling a turn sole with a last, and breaking down the entire shank and forepart margin of the 115 sole by pressure on that portion of the margin which projects beyond the edge of the last prior to the first lasting operation.

2. The method of preparing turn soles for lasting which comprises assembling a turn 120 sole with a last, and breaking down the margin over the edge of the last by pressure applied simultaneously along an extended portion of said margin.

3. The method of preparing turn soles for 125 lasting which comprises assembling a turn sole with a last, and breaking down the margin of the sole about the tip of the toe over the toe end of the last by pressure applied simultaneously to the whole of the 130

margin from a point at one side of the tip to a point at the other side thereof.

4. The method of preparing soles for turn shoes for the lasting operation which comprises assembling a sole on a last with its margin extending over the edge of the last, breaking down the projecting margin at the lateral edges of the sole by a pressure applied progressively on small portions of 10 said margin, and breaking down the margin at the tip of the toe and sides adjacent said tip by a pressure applied simultaneously about the entire toe.

5. The method of preparing soles for the lasting operation for turn shoes which comprises securing the sole to a last bottom of less area than the sole whereby the edge of the last is adapted to act as an anvil over which the margin may be broken down, and 20 then pounding down the margin over said edge progressively along each lateral edge of the sole and simultaneously upon both sides at the tip of the toe.

6. The method of making turn shoes

which comprises assembling a turn sole with 25 a last, breaking down the projecting margin by a moulding pressure on said margin, and then assembling and lasting an upper over said broken down margin.

7. The method of making turn shoes 30 which comprises temporarily securing a previously shouldered turn sole on a last and locating said sole on the last by placing the shoulder opposite the edge of the last bottom, then moulding the margin of the sole 35 which is outside of said shoulder, and thereafter assembling an upper on the last and lasting said upper over the moulded sole margin.

8. That step in the method of making 40 turn shoes which consists in moulding the margin of the sole, after assembly on a last and prior to the assembly of the upper on the last, in two stages, to wit: at the lateral edges thereof and about the tip of the toe. 45

In testimony whereof I have signed my name to this specification.

MICHAEL F. BROGAN.
